OUTBOARD MOTOR BRACKET

Edwin C. Hitzemann, St. Paul, Minn.

Application January 26, 1946, Serial No. 643,578

6 Claims. (Cl. 224—29)

1

My invention relates to an improvement in an outboard motor bracket wherein it is desired to provide a simple bracket for supporting an outboard motor in the trunk compartment of an automobile.

Various types of brackets have been produced for supporting outboard motors in an upright position either for use in displaying the same, or for use in temporarily holding the same. Cases have also been provided for enclosing the motors, these cases having a flat panel along one side thereof for holding the motor in predetermined position.

It is the object of the present invention to provide a simple bracket which is mounted within the trunk or luggage compartment of an automobile and which serves to hold the motor in set position during transportation. The motor may be easily secured to the bracket without the use of special tools or equipment and in an extremely short period of time. At the same time, however, my bracket acts to support the motor in fixed position so that it may be carried without danger of rolling or tilting when the automobile starts or stops suddenly. As a result my bracket serves to protect the motor during transportation.

An outboard motor is often provided with projecting portions which may be easily damaged if the motor is rolled axially while resting upon a flat surface. Spark plugs often project outwardly from the motor and are easily broken if the motor rolls from its intended position. Furthermore the fuel lines and other relatively delicate parts may easily become damaged should the motor roll over in transit.

It is an object of the present invention to provide a bracket which may be secured to the deck or flooring or the luggage compartment of an automobile and which is provided with an arm extending in substantially parallel relation to the deck. The outboard motor is secured to this arm by means of the clamps ordinarily employed to secure the motor to the rear of a boat. Thus in securing the motor to the bracket it is only necessary to place the motor horizontally into the compartment so that the bracket clamps embrace the horizontal arm of the bracket, and to tighten the clamps so as to hold the motor in place.

A feature of the present invention resides in the provision of an adjustable bracket which may be adjusted in height to compensate for various sizes of motors. The bracket is formed in two main parts which are vertically adjustable so that the proper spacing is provided between the hori-

2

zontal arm at the top of the bracket and the deck or floor of the luggage compartment.

A further feature of the present invention lies in the provision of a bracket formed with a base portion preferably channel shaped in cross section and an upper portion which adjustably slides within the channel of the base portion. As a result the two parts of the bracket are firmly and rigidly held in place so that no twisting or pivoting may take place therebetween.

An added feature of the present invention lies in providing an upper bracket arm with relatively soft upper and lower surfaces so that the motor clamps may firmly engage the same. A strip of wood is provided above and below the relatively rigid metal arm of the bracket. The clamps engage against one of these wooden members while the fixed bracket portions engage against the opposite wooden member. As the clamps of an outboard motor are usually designed to hold the motor engaged to the wooden end of a boat, these clamps may serve their intended purpose in the usual manner. By providing a wooden surface on either side of the metal arm, the bracket and clamp may engage these wooden surfaces without requiring a bulky wooden support which would otherwise be necessary.

These and other objects and novel features of my invention will be more clearly and fully set forth in the following specification and claims.

In the drawings forming a part of my specification:

Figure 1 is a rear elevational view of a motor vehicle showing the outboard motor supported by my bracket therein.

Figure 2 is a perspective view of the assembled bracket in readiness for use.

Figure 3 is a perspective view of the bottom portion of the bracket showing the construction thereof.

Figure 4 is a perspective view of the upper portion of the bracket showing the construction thereof.

Figure 5 is a front elevational view of a slightly modified form of bracket construction.

The bracket A is designed for supporting an outboard motor B in suitable position for transit within the luggage compartment 10 of an automobile C. The luggage compartment 10 may be of any desired shape or form as long as the size of the same is sufficient to accommodate the motor and bracket. The luggage compartment 10 is shown provided with an opening 11 at the rear thereof which is normally closed by a closure 55 12 transversely pivoted at 13 to the body of the

car. The compartment shown is provided with a lower compartment 14 suitable for holding a spare tire 15. A false floor or deck 16 extends over the tire 15 and acts to support luggage and the like. Obviously the bracket A may be secured either to the floor of the compartment or to the deck 16 thereof, depending upon the structure of the particular type of car on which the bracket is used.

The motor B is provided with clamping brackets 17 which are of channel shape to extend over the upper edge of the rear of a row boat or the like. Threaded clamps 19 extend through one side of the brackets 17 to clamp the motor firmly to the boat. The threaded clamps 19 are provided with clamping ends 20 and handle ends 21 by means of which the clamps may be rotated.

In usual construction the clamps 17 are pivotally connected to the body of the motor B so that the angle between the clamps and the motor may be changed if desired. As the particular structure of the motor itself is not of importance in the present invention, the manner in which the clamps 17 are connected to the motor is not disclosed in detail.

The bracket A includes the lower or base portion 22 and the upper or arm portion 23. These bracket portions are adjustably secured together as will be later described in detail.

The base portion 22 of the bracket is channel shaped in cross section and includes a flat base portion 24 and opposed side flanges 25. The base portion 22 is substantially L-shaped in form, thereby providing a base portion 26 and a standard portion 27. A pair of apertures 29 are provided in the base portion 26 by means of which bolts or screws 30 may extend to hold the bracket in place. In the form illustrated the bolts 30 extend through the base portion 26 and through the deck 16 to hold the bracket firmly secured to the base.

The standard portion 27 of the bracket element 22 is provided with a pair of spaced bolt holes 30 therethrough near the upper extremity thereof. These bolt holes 30 extend through a base portion of the channel between the flanges 25 and serve as bolt holes for the bolts connecting the two parts of the bracket.

The upper section 23 of the bracket A includes a standard portion 31 and an arm 32 extending angularly therefrom. The standard portion 31 is provided with a series of bolt holes 33 therethrough which are spaced a distance equal to the spacing between the bolts 30. As a result the bolts 34 which clamp the two bracket portions together may extend through the holes 30 and through any two of the holes 33, thereby holding the two bracket portions in properly adjusted relation.

The arm 32 is provided with a pair of strips 35 and 36 of hard wood or the like, lying above and beneath the same. The wooden strips are secured to the arm by screws or bolts 37. In preferred construction screws 32 extend through the strips 35 through holes in the arm 32 and anchor in the strip 36. The ends of the screws or bolts are preferably countersunk so that the clamps on the motor engage against the wooden surface.

The manner in which the bracket A is attached is clearly indicated in Figure 1 of the drawings, it being understood, however, that while the position indicated is preferred, the bracket may be directed in a different direction if it is so desired. The standard portions 27 and 31 of the two bracket portions are preferably

in right angular relation to the base portion 26 and the arm 32 respectively. However, it is not entirely essential that the right angular relation be preserved as long as the base member 26 and the arm 32 are in substantially parallel relationship.

In Figure 5 of the drawings I disclose a modified form of bracket construction D which is similar to the bracket A. The bracket D includes 10 a bottom or base element 22 identical to the base element previously described. The upper bracket portion 39 differs from the similar portion 23 of the bracket A in that the plane of the arm 41 is inclined. This construction is desirable because 15 of the fact that the rear ends of most boats tilt inwardly and downwardly so that the brackets 17 are usually adjusted in angular relation to the motor B to hold the motor in approximate vertical position. By inclining the arm 41 as indicated in Figure 5 the motor brackets may be attached thereto without changing this angular 20 adjustment of the brackets 17. In most instances the bracket A will permit the necessary tilting of the motor B without adjusting the brackets 17. In some instances, however, it is preferable 25 to tilt the arm 41 as indicated in Figure 5.

In accordance with the patent statutes, I have described the principles of construction and operation of my outboard motor bracket, and while I have endeavored to set forth the best embodiments thereof, I desire to have it understood that obvious changes may be made within the scope of the following claims without departing from the spirit of my invention.

I claim:

1. An outboard motor bracket for use in the luggage compartment of an automobile, the bracket comprising a generally U-shaped portion including a substantially horizontal base portion, a standard portion extending upwardly from said base adjacent one end thereof, and a substantially horizontal arm extending from the upper end of said standard portion generally parallel to, and spaced above, said base, said arm being positioned for engagement by the motor clamping brackets of the outboard motor.

2. A clamping bracket for use in combination with an outboard motor and an automobile luggage compartment, the bracket including a substantially horizontal base, an adjustable standard portion extending upwardly from said base adjacent one end thereof, and a substantially horizontal arm at the upper end of said standard generally parallel to, and spaced above, said base, said arm being designed for engagement in the clamping brackets of the outboard motor.

3. An outboard motor bracket for use in the luggage compartment of a car, a bracket comprising a substantially horizontal base, means securing said base to the flooring of the luggage compartment, a standard extending upwardly from the base adjacent one end thereof, an arm extending laterally from said standard generally parallel to, and spaced above, said base, and wooden strips secured to opposite sides of said arm, said arm being designed for engagement with the motor bracket clamps of the outboard motor.

4. An outboard motor bracket for use in the luggage compartment of a car, the bracket comprising a base portion, means securing the base portion to the floor of the luggage compartment, an adjustable standard portion extending upwardly from the base, and an arm extending substantially horizontally from said standard,

said arm including a central rigid member, and a pair of strips of relatively softer material secured thereto, said arm being designed for engagement with the motor clamps of the outboard motor.

5. An outboard motor bracket for use in the luggage compartment of a car, the bracket comprising a base member substantially channel shape in cross section, said base being bent upwardly to provide a standard portion substantially channel shape in cross section, a second bracket member embraced within the channel of said standard portion and adjustably secured thereto, said second bracket portion having a transverse arm thereupon designed for engagement by the bracket clamps of an outboard motor.

6. An outboard motor bracket for use in the luggage compartment of a car, the bracket comprising a base member substantially channel shape in cross section, said base being bent upwardly to provide a standard portion substantially channel shape in cross section, a second bracket member embraced within the channel of said standard portion and adjustably secured thereto, said second bracket portion having a 25

transverse arm thereupon designed for engagement by the bracket clamps of an outboard motor, said arm including a relatively rigid center member and upper and lower wooden strips secured to said arm and extending above and below the same and secured thereto.

EDWIN C. HITZEMANN.
